UNITED STATES PATENT OFFICE.

LEO A. BRIGEL, OF CHEVIOT, OHIO.

AUTOMOBILE-HEATER.

1,095,799.

Specification of Letters Patent.

Patented May 5, 1914.

Application filed October 2, 1909. Serial No. 520,659.

To all whom it may concern:

Be it known that I, LEO A. BRIGEL, a citizen of the United States, residing at Cheviot, in the county of Hamilton and 5 State of Ohio, have invented certain new and useful Improvements in Automobile-Heaters, of which the following is a specification.

My invention relates to improved automobile heating apparatus.

One of its objects is to provide apparatus adapted to be permanently attached to the car and when required to utilize the waste heat from the engine exhaust to keep the 15 occupants comfortable.

Another object is to provide an improved form of radiator employing a liquid heating medium which in turn is adapted to receive heat from the motor or engine.

20 Another object is to provide means for obtaining a circulation of the liquid heating medium.

It further consists in certain details of form combination and arrangement all of 25 which will be more fully described in connection with the accompanying drawings in which:

Figure 1 is a diagram in top plan view of my improved apparatus. Fig. 2 is a side 30 elevation of the same. Fig. 3 is a central vertical section through one of the radiators on line *v v* of Fig. 1.

In the accompanying drawings A represents the propelling motor of an automobile, 35 which may be a steam engine but is preferably an explosion engine. B represents the exhaust pipe leading therefrom.

C C' represent radiators or heaters preferably let into the floor *b* of the car in front 40 of the respective car seats and with their upper faces flush with the car floor. Said radiators comprise hollow metal shells which may be cast if desired, but are preferably formed from stamped or drawn sheet metal 45 sections which are united by welded joints at *c c'*. A partition D divides each of said radiators into two compartments *d d'*. The compartments *d* receive the heated exhaust which is diverted to the desired extent from 50 the exhaust pipe B by means of a controlling valve *d²*, from which the diverted exhaust passes by pipe E to compartment *d* of radiator C thence by pipe *e* to compartment *d* of radiator C' and thence by pipe *e'* is 55 returned to the exhaust pipe B and escapes to the air through the muffler B'. The com-

partments *d'* of the respective radiators are filled with a liquid heating medium, preferably water with the addition of a substance to sufficiently lower its freezing point to 60 avoid freezing under normal conditions. The liquid being in contact with the part of the radiator in contact with the floor and articles of clothing of the occupants prevents temperatures high enough to do damage, 65 and provides a uniform heat of the quality required.

H represents a tank or reservoir which is preferably located beneath one of the car seats and at a level slightly above the radiators. Said tank is connected by a pipe *h* with the compartments *d'* of the respective radiators to provide an escape from said compartments to said tank of any vapors generated therein. A pipe *h'* is also preferably provided at the opposite end of tank H and connected thereto at a lower level than pipe *h*, said pipe *h'* being also connected to the compartments *d'*, and thereby providing for a circulation of the liquid from tank H 75 by pipe *h'* through the respective compartments *d'* and back to tank H by pipe *h*. The tank H is preferably provided with a blow off valve K to prevent excessive pressures.

The mechanism herein illustrated and described is capable of considerable modification without departing from the principle of my invention.

Having described my invention what I claim is:

1. In a mechanism of the character described, a motor, an exhaust pipe leading from said motor, a radiator having a substantially horizontal upper face to occupy a position flush with the floor of a car and comprising a shell divided by a cap shaped partition into an upper chamber and a lower chamber with the upper chamber embracing the top and sides of the lower chamber, connections at the side of said radiator through 90 which to circulate a liquid to and from said upper chamber, and connections near opposite sides at the bottom of said lower chamber to circulate the motor exhaust from said exhaust pipe through said lower chamber. 100

2. In a mechanism of the character described, a motor, an exhaust pipe leading from said motor, a radiator having an upper face to occupy a position substantially flush with the floor of a car and comprising a shell divided by a partition into an upper chamber and a lower chamber separated at its top 110

2
and sides by said partition from said upper compartment, said upper compartment being provided with pipe connections at its sides to provide for the circulation of a liquid heating medium therethrough, and said lower compartment being connected at its under side at one end by a valve controlled pipe with said motor exhaust pipe and at the opposite end of its lower side with an exit port to provide for circulating a regulated portion of the motor exhaust through said lower chamber.

3. In a mechanism of the character described, a motor, an exhaust pipe leading from said motor, a radiator comprising a shell divided by a substantially horizontal partition into an upper compartment adapted to contain a liquid heating medium

and a lower compartment provided with a valve controlled inlet pipe leading from said exhaust pipe, and an exit port to provide for a circulation of the motor exhaust through said last named compartment, a tank located at a higher level than said radiator, a pipe connecting the upper portion of said tank with said first named compartment of the radiator, and a pipe connecting the lower portion of said tank with said first named compartment of the radiator.

In testimony whereof I have affixed my signature in presence of two witnesses.

LEO A. BRIGEL.
